UNITED STATES PATENT OFFICE

96,440

DESIGN FOR AN IRONING MACHINE CABINET

Alpheus W. Altorfer, Peoria, Ill.

Application April 2, 1934, Serial No. 51,291

Term of patent 14 years

To all whom it may concern:

Be it known that I, Alpheus W. Altorfer, a citizen of the United States, residing at Peoria, in the county of Peoria and State of Illinois, have invented a new, original, and ornamental Design for an Ironing Machine Cabinet, of which the following is a specification, reference being had to the accompanying drawing, forming part hereof.

Fig. 1 is a front perspective view of an ironing machine cabinet, in an open position, showing my new design; and

Fig. 2 is a perspective view of the same in a closed position.

I claim:

The ornamental design for an ironing machine cabinet, as shown and described.

ALPHEUS W. ALTORFER.
